CONE JACKET FORMING MACHINE

Jacob Cutler, Matapan, Mass., assignor to Maryland Baking Company, Inc., Baltimore, Md., a corporation of Maryland

Application July 10, 1943, Serial No. 494,239

6 Claims. (Cl. 93—49)

1

My invention relates to machines for folding paper blanks into conical form and sealing the overlapped edges together.

More specifically, the invention relates to machines for forming frustro-conical jackets for covering the stems of ice cream cones.

Primarily, the present invention has for its object to provide a simple, portable, single-unit machine that can be manufactured at a relatively low cost and sold at a reasonable price to the smaller ice cream cone manufacturers and dealers who may wish to make their own jackets.

The invention further has for its objects to improve the several mechanisms employed in such machines, as, for example, the blank transfer mechanism, the blank forming mechanism, and the formed-jacket discharging mechanism.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is a top plan view of the machine which embodies my invention.

Fig. 2 is a side elevation thereof.

Fig. 3 is a side elevation of the side opposite that of Fig. 2.

Fig. 4 is an enlarged detail vertical sectional view on the line 4—4 of Fig. 5.

Fig. 5 is a horizontal sectional view on the line 5—5 of Fig. 4.

Fig. 6 is a detail plan view below the line 6—6 in Fig. 4.

Fig. 7 is an enlarged plan view of the glue-applying unit.

Fig. 8 is a sectional view on the line 8—8 of Fig. 7.

Fig. 9 to Fig. 13, inclusive, are detail sections on the line 9—9 of Fig. 5, showing the different positions of the parts during the forming, pasting, and discharging of the jacket.

Fig. 14 to Fig. 22, inclusive, are detail views of the cams and cam levers for operating the several moving parts of the transfer, folding, and

2

discharging mechanisms and the vacuum controls.

Fig. 23 is an enlarged detail elevation of the one-way clutch drive for the discharge mechanism.

Fig. 24 is a detail view, partly in section, with the leaf-spring 190 removed.

Fig. 25 is an enlarged detail section on the line 25—25 of Fig. 1.

Fig. 26 is a vertical cross section on the line 26—26 of Fig. 25.

Fig. 27 is a detail cross-sectional view through one of the brake devices.

Fig. 28 is a detail elevation of the glue applicator shaft and its fingers and cam.

Fig. 29 is a cross section on the line 29—29 of Fig. 28.

Fig. 30 is a vertical section of the suction control valve.

20 In the drawings, like numerals and letters of reference indicate like parts in all the figures.

In general

In general, the machine embodies a supporting frame, a drive motor, a vacuum pump, a magazine for jacket blanks, a glue-applying device to apply glue or paste to the blanks, a means for conveying the blanks from the magazine, a mandrel and a means to fold the blanks around the mandrel, and a mechanism for stripping the jackets from the mandrel and discharging the same from the machine.

The frame of the machine comprises vertical corner angle bars 1, bottom side and end angle bars 2, top angle bars 3, intermediate side angle bars 4, vertical supports 5 and horizontal supports 6, 6a, 6b, 6c, 6d.

Mounted on the support 6 is a driving electric motor 7 and a vacuum pump 11. The motor 7 has a drive pulley 9 and a smaller drive pulley 10 secured to its shaft 8 (see Fig. 3), while the pump shaft 12 carries a large driven pulley 13. The pulleys 9 and 13 are connected by a belt 14, thereby constituting a reduction-speed drive for the pump. The small pulley 10 is connected by a belt 17 to a large pulley 16 on a stub shaft 15. The pulley 16 is secured to the stub shaft 15 as is also a pinion 18 which meshes with a master gear 20 on a cam-shaft 19.

The cam-shaft 19 is journaled in suitable bear-

ings 21 that are mounted on supports 22 which are carried by the side bars 2 of the frame.

Secured to the bars 4 is a transverse angle bar 23, there being another such bar 23 mounted below and secured to the supports 22. Secured, at suitably spaced intervals, to the bars 23 are vertical supports 24 for the pivots 255 of the several cam levers shown in detail in Figs. 14 to 22 inclusive.

The operating cams

Referring now particularly to Figs. 14 to 22 inclusive, it will be seen that the several cams comprise split clamps that carry the various cam rollers. In Fig. 14 is shown the edge lapper cam 25 and its cooperating lever 27. In Fig. 15 is shown the cam 29 and its lever 30 which effect the raising and lowering of the device which lifts the blank to and partly folds it around the mandrel. Fig. 16 shows the cam 31 and lever 32 which effect the operation of the glue-applicator. Fig. 17 shows the cam 33 and its lever 34 which operate the throw-off belt lifting and lowering means. Fig. 17 also indicates the cam 35 and shows its lever 36 which operate the throw-off and discharge belt's drive.

Fig. 18 shows the jacket blank carrier advancing cam 37, the jacket blank carrier retracting cam 39 and the respective arms 38 and 40 of the lever 41 which cooperate with the cams 37 and 39.

Fig. 19 shows the cam 42 and its lever 43 which serve to effect the raising and lowering of the jacket blank carrier when the carrier is beneath the magazine. Fig. 20 shows the vacuum control cam 44 and its lever 45. Fig. 21 shows the blade-operating cam 46 and its lever 47, while Fig. 22 shows the edge sealer operating cam 26 and its lever 28.

The blank-folding mechanism

On a base plate 48, which is secured to the frame of the machine, are pairs of spaced standards 49 and 50. A cross bar 51 (see Figs. 2, 3 and 4) is borne on the tops of the standards 49. On the bar 51 there is secured plates 52 on which spaced angle guides 53 (see Figs. 1 and 5) are mounted so as to provide T-slots in which slides 54 and 56 are operable.

A forked blade 55 is rigidly secured to the slide 54, while a plate 58, carrying spaced rollers 252, is hingedly mounted, at 57, on the slide 56. A stud 59, secured to slide 56, passes up through a slot (Fig. 5) in plate 58 and carries a spring 60 and an adjusting nut constantly to exert a downward pressure on plate 58 for a purpose later to appear.

At the respective sides of the machine and on the top bars 3 are mounted bearing brackets 61, 61a carrying shafts 62, 62a. Secured to the respective shafts are arms 63, 63a which are connected to the respective slides 54, 56 by connecting rods 64, 64a (Fig. 1). To the shafts 62, 62a are respectively secured arms 65, 65a to which the connecting rods 66, 66a are respectively connected. The rod 66 connects to cam lever 27, while the rod 66a connects to cam lever 28, hereinbefore referred to.

Secured to the cross bar 51 is a mandrel 70 having a shank 71 and a longitudinally disposed blade groove 72. The blade groove is located on top of the mandrel and receives the blade 76. A pair of vertical slotted guides 75 extend alongside of the shank 71 and a part of the mandrel 70 and have lugs 83 which pass into holes in the

mandrel and are secured to the bar 51 by screws 84 (Figs. 4 and 5). Adjustably mounted on the bar 51 are bracket bars 69 which carry the bracket 68 on which the magazine 67 is mounted (see Fig. 5).

The mandrel and shank have a bore 73 from which ports 74 lead to atmosphere. The blade 76, which is longitudinally slideable in the groove 72, is secured at its rear end to a carrier 77. The ends of the carrier pass through the slots in the member 75 and carry rollers 78 and collars 79. The blade 76 has holes 254 which register with certain of the ports 74 when the blade is drawn back.

The forked ends of the lever arms 80 that are secured to a shaft 81 (Figs. 1 and 4) engage the rollers 78. The shaft 81 is journaled in bearing standards 82 that are secured to the cross bar 51. An arm 87 forms with the arms 80 a bell-crank lever, to the arm 87 of which a connecting rod 88 (Fig. 3) is pivoted. The rod 88 is also pivoted to the cam lever 47, hereinbefore referred to.

The guides 75 are joined, at their forward ends, by a bridge 85 that carries an adjusting screw 86 for holding the blade 76 down in its groove 72. It will be noticed that the groove 72 does not extend to the apex or outer end of the mandrel 70, but tapers off about one-third the distance between the outer end of the mandrel and the bridge 85 (Figs. 4 and 5). Therefore, when the blade 76 advances, it will ride up over the top of the tip end of the mandrel for a purpose presently made clear.

The blank transfer mechanism

Slidably mounted on rigid guide rods 90 is a carriage 91 (Fig. 1) which carries a bracket 89. Oil pads 92 are located on the rods 90 between furcations of the sliding carriage 91 and slide with it along the rods to lubricate the bearing surfaces. 93 is a back-stop for the carriage and is secured to the frame adjustably.

Vertically, slidably mounted in suitable bearings in the bracket 89 (Figs. 3, 4 and 6) is a rod 95 to the top of which is rigidly secured an offset bracket 98, to which the blank removing and carrying forked member (or transfer member) 99 is rigidly fastened, as at 100. The rod 95, between the upper and lower bearings 94, carries a spring 97 and a spring-tension-adjusting collar 96. The shaft or rod 95 is held from turning on its axis by means of an arm 258 whose end is slideable in a vertically slotted stud 256 that is secured to the bracket 89 (Fig. 3).

The jacket blank transfer member 99 includes converging arms 101 having along their upper faces longitudinal grooved portions 102. Ducts 104, 105 are formed in the member 99 and communicate with ports 103 in the grooved portions 102 (Fig. 6). The duct 105 is connected to a flexible duct 107 by means of a nipple 106. The duct 107 is connected to the suction regulating valve 125 that communicates with the suction pump 7 via fitting 127, flexible duct 124, rigid duct 123, suction control valve 119, and flexible duct 122 (Figs. 2 and 3).

Brackets 108, secured to the frame of the machine, carry a rock shaft 109 and an arm 110. A connecting rod 114 connects arm 110 with cam lever 43 (Figs. 2 and 19). Secured to the shaft 109 is a lever or rocker arm 111 having a beveled edge 112. The lever 111 lies in the plane in which the rod 95 is moved by the carriage 91 so that when the carriage is in its retracted or back position the rod 95 will have ridden up onto the end

of lever 111 (Fig. 3). A spring 113 connects the rear end of lever 111 with the frame of the machine and constantly tends to urge the lever 111 to lower its beveled end.

The sliding carriage 91 also has a slotted lug 115 to which is pivoted one end of a link 116, the other end of which is pivoted to the cam lever 41.

The suction control and regulating valves

The suction control ("on" and "off") valve 119 has its stem 120 linked to a lever 118. One end of the lever 118 is pivoted to a bracket 117, while the other end thereof is joined by a spring 132, constituting a yieldable connection, to the connecting rod 131 that joins to cam lever 43 (Figs. 2 and 20).

The valve 119 (Figs. 2 and 20) is of a special kind in order to effect properly the timely action of the suction means. This valve comprises a casing having a valve seat 259 for controlling the main passage. The neck 262 of the valve has an annular groove 263 from which leads a port 266 to the nipple 267 to which the flexible duct 143 connects.

The stem 269 of the valve has the valve plug 261 which cooperates with the seat 259. The stem also has a bore 264 entering its lower end. Ports 265 effect communication between the bore 264 and the groove 263 when the plug 261 is seated, i. e. when the stem 269 is pressed down by the lever 118, thereby cutting off the suction to the fork fingers 161 and the mandrel and establishing suction in the pipe 140.

The valve stem 269 is held down only for a short time, namely only while head 133 is taking a blank off the blank transfer member 99 (Fig. 14) and elevating it to the mandrel 70. As soon as pipe 139 contacts the mandrel and is depressed to the bottom of the groove 138, valve 119 returns to normal position i. e., with passage via seat 259 open and passage via 264, 263, and 266 closed.

The vacuum regulating valve 125, hereinbefore referred to, regulates the degree of vacuum in the transfer fork, while a valve 126 that is connected to fitting 127 controls the degree of vacuum in the mandrel. A rigid pipe 128 has one end connected to valve 126 and the other end to a flexible pipe 129 that is in turn connected to the rigid pipe 130, which is secured to the shank 71 of the mandrel 70 and communicates with the bore 73 thereof (Fig. 4). By adjusting the valves 125 and 126, the proper degree of suction at each place may be had when valve 119 is open.

The blank folding mechanism

This mechanism includes the forked blade 55, the roller carrying plate 59, and the mechanism which is best shown in Figs. 4 and 9 to 13 inclusive.

Located for up and down movement beneath the operative part of the mandrel 70 is a grooved folding head 133 that is carried by a vertically reciprocatable rod 135. The rod 135 is mounted in a bearing boss 134 (Fig. 3) depending from the plate 48 and is pivoted at its lower end to a lever 136 that is fulcrumed in a second boss 144, also depending from the plate 48. The lever 136 is connected, by a connecting rod 137, with cam lever 36 (Fig. 16).

The groove 139 in the head 133 conforms to the shape of the mandrel 70. The head has a bore 139, intersecting the groove 138, through which bore a pipe 140 projects. The pipe 140 is held with its upper or free end located on a level preferably slightly below the level of the 75

top of the head, by means of a spring 142 and a stop collar 141. The lower end of the pipe 135 is connected to a flexible duct 143 (Figs. 2 and 3) which in turn connects to and is controlled by the valve 119.

The jacket throw-off mechanism

Mounted in suitable bearings on the standards 50 is a shaft 145 on which is secured a grooved belt pulley 159 and on which is pivoted a pair of arms 149 whose free ends carry a shaft 150. Connected arms 156 are pivoted to shaft 150 and in turn carry a shaft 165 on which is journaled a grooved pulley 158 (Fig. 25). A grooved pulley 157 is journaled to turn freely on shaft 150, which shaft is also free to be rocked in its bearings in arms 149. Arms 156, however, are secured to and turn with shaft 150.

An arm 152 (Fig. 2) is also secured to shaft 150. A connecting rod 153 (made in two parts, slidably and spring loaded as at 155, connected together) joins arm 152 to cam lever 34. A return spring 154 (Figs. 2 and 17) serves constantly to return pulley 158 to the full-line position in Figs. 2 and 3 (dotted-line position, Fig. 25) when cam lever 34 is disengaged by cam roller 35. Cam roller 35 is behind roller 33 and not visible in Fig. 17. A V-type belt 160 takes around pulleys 158, 157 and 159.

20 A belt tightener is provided to keep belt 160 taut. It comprises a pair of arms pivoted respectively to the arms 149 at 162 and carrying between them a grooved roller 161 which rides on the belt 160 under pressure of the spring 163.

25 A pair of bars 166, adjustable and depending by links 167—168 from arms 149, carry spaced, grooved, belt-engaging rollers 170 for engaging and holding straight the lower flight of belt 169.

The links 167 are pivoted at 162, while the links 168 are slotted and secured by screws 169 to the arms 149.

30 Blocks 148 are adjustably secured to the uprights 50 on the opposing faces thereof and carry a shaft 147 on which is secured a grooved pulley 174 and a gear wheel 146 which meshes with a similar gear wheel 148 secured to shaft 145 so that motion imparted to shaft 145 is transmitted to shaft 147.

35 Arms 171 are pivoted to shaft 147 and at their free ends carry a grooved pulley 173. An endless V-type belt 175 takes over pulleys 173, 174 and over a guide 176 whose bracket arms 177 are adjustably secured by screws 178 to the arms 171 (Figs. 25, 26). The upper flight of belt 175 is held up against the lower flight of belt 160 by means of the spring 163 and a second spring 179 that connects an arm 149 with an arm 171. The pulley 173 lies below pulley 157, while arms 156 and pulley 158 overhang pulley 173.

40 Collars 151 on shaft 150 engage adjustable stop screws 180 secured to plates 52, for lining up the throw-off device with the mandrel.

45 The shaft 145 is turned at proper intervals by means of a one-way friction clutch device which will now be explained by reference, particularly, to Figs. 2, 23 and 24.

50 Secured to the shaft 145 is a clutch wheel 181 having a lateral flange over which is loosely fitted the slotted ends of arms 184. The arms 184 have their inner ends resting in recesses 183 in a collar 182 loose on shaft 145, the collar having an arm 191 that has a T-slot to receive the T-block 192 to which is pivoted, at 193, the connecting rod 194 that connects with the cam lever 36 (Fig. 17).

55 Each arm 184 carries a leaf spring 185. To

the collar 182 is fastened rigid arms 186 having threaded slotted ends 187 to receive the adjusting screws 188. Clamp screws 189 are provided for the split ends 187. A leaf-spring 190, held on the shaft by a collar 191, keeps the arms 184 in place (Fig. 23).

A bracket 195 supports a trough 196 into which the finished jackets are delivered.

The adhesive-applying mechanism

Referring now more particularly to Figs. 1, 2, 7 and 8, it will be observed that a plate 197 is mounted on the frame of the machine. The pot 198 for adhesive is secured on this plate and the power transmitting mechanism therefor is also mounted on the plate.

The pot 198 has a cover 199 which is cut away, at 201, to provide a filling opening and at 200 to allow clearance of the adhesive rollers.

Journalized in suitable bearings 206 is a shaft 203 which passes through the pot and carries the lower adhesive-gathering roller 202. Outside the pot the shaft 203 carries a gear 204 and a driven gear 205, the latter gear meshing with a gear 207 on a shaft 208 which is journaled in a bearing 209.

Journalized in a bearing 212 is a drive shaft 211. The shafts 211 and 203 are connected by bevel gears 210 and are driven by a sprocket and chain connection 213, 214, 215 from cam shaft 19.

Cast with the pot 198 are side posts 216 between which, at 217, is pivoted a skeleton frame 218 which carries the shaft 222 of the upper adhesive-spreading roller 223. The frame 218 has an ear 219 which is adjustably connected to the rigid threaded post 221 to hold the rollers 202 and 223 in contact or so close together as to provide a thin layer of adhesive on the surface of roller 223. The post 221 is secured to the base extension 220 of the adhesive pot 198, as best shown in Fig. 8.

A gear 224, fast to shaft 222, meshes constantly with gear 204.

Standards 225 are fastened to the pot 198 and carry a shaft 227 on which is secured a skeleton frame 226, in the free ends of whose arms is journaled a shaft 232 which has a back 233 and a clamp plate 234 between which the applicator finger-plates 236 are secured by means of screws 235 (Fig. 28). The frame 226 has an arm 228 to which is pivoted a connecting rod 229 that connects to the cam lever 32 (Figs. 3 and 16). A spring 240 connected to lever 32 and anchored to the frame of the machine continuously tends to swing the frame 226 counterclockwise in Fig. 8.

The frame 226 has lugs 230 carrying adjustable stop screws 231 that rest on the top ends of the posts 216.

The shaft 232 carries a gear 237 that normally meshes with gear 234. A cam 238, fixed to the shaft 232, cooperates with the fixed cam track 239 that is mounted on the posts 216.

As the blank transfer member is raised to contact the lowest blank in the magazine, the applicator 238, 226 is also raised and the fingers 236 move alongside the adjacent furcation 101 of the member 99 so as to contact the blank as it is being pulled down by suction onto the member 99 in order to give a wiping action of the blank over the edges of the applicator fingers to "brush" on the adhesive. If desired the fingers may be timed to apply the paste before the blank is sucked down.

As the machine is quite rapid in its operation, I provide damping brakes on the shafts 62, 62a

and 81, the construction of which is best shown by way of example, in Fig. 27. Referring to that figure, it will be seen that two brake shoes 241 and 244 carry liners 242 for engaging the particular shaft whose movements are to be deadened; screw bolts 245, spring-loaded as at 246, pass loosely through the short block 244 into the long block 241. The long block is anchored against turning by means of a bolt 243 passing through it and threaded into a fixed support, as 61a for example. The degree of friction applied to the shaft may be regulated by screwing in or backing off the screws 245 as may be desired.

Electric power lines (not shown) are led into box 247 where the power is controlled by an "on and off" switch 248 of any approved kind. Armored cable 249 conveys current to the motor 7 from the switch box 247.

Air is discharged from pump 11 through a duct 250.

The machine may be provided with casters 251 for transporting purposes.

The magazine 67 is provided with leaf-springs 253 and a finger 268 for holding the pack of blanks from falling out of the magazine, and for this purpose the springs 253 have their lower ends 257 bent inwardly (Figs. 4 and 5).

Operation

30 Assume the parts to be in the position shown in Figs. 1, 2 and 3. At this time the blank transferring mechanism is in its retracted position, the fork 99 lying directly beneath the magazine 67.

35 Cam 42 is just about to engage lever 43 (Fig. 19) to cause lever 111 to lift rod 95 and the jacket-transferring member 99 in order to gather a jacket blank from the magazine. Continued operation of the machine causes the member 99 to be raised up to the magazine (see dotted lines, Fig. 4); causes plate 58 to advance in the direction of the arrow (Fig. 12) to the position shown in Fig. 13; causes valve 119 to open, allowing pump 11 to produce a suction in grooves 102 of the transfer fork, thereby to draw down the bottom blank from the magazine. As soon as the blank has adhered to the arms 101 of the fork 99, the fork is instantly lowered, whereupon the carriage 89 is advanced toward the mandrel 70. As the carriage advances, taking with it the blank, the head 133 remains at its lower position so that it will be straddled by the fork when the fork reaches its farthest advanced position (Fig. 9).

As soon as the fork 99 reaches the position 55 shown in Fig. 9, the head 133 rises and the arms 156 are swung down to bring the belt 160 down into position to throw off the previously formed jacket w (Fig. 9), from the mandrel 70; at the same time the jacket is lifted from the fork arms 101. By the time the head has risen from the position shown in Fig. 9 to that shown in Fig. 10 the previously formed jacket will have been thrown off and the fork 99 will have been retracted.

65 Further movement causes head 133 to continue rising until the position of Fig. 11 is reached, at which time the jacket blank will have been pressed to and partly about the mandrel by the head 133. As the blank is placed against the mandrel by the head 133 the blade 55 is advanced and as soon as the blade reaches the dotted line position of Fig. 11 the roller-carrying plate 55 starts to advance. First the blade 55 moves to its extreme advanced position (Figs. 1 and 12) and then the rollers 252 roll the blank so that the side

edges of the blank overlap. The adhesive having been applied to the blank before or as it was gathered from the magazine (as will more fully appear later) the rollers cause adhesion to take place. When the rollers 252 have advanced far enough to press the blank edges together, blade 55 recedes (see arrow adjacent 55) and after rollers 52 have reached a position slightly in advance of that shown in Fig. 13 slide 56 and plate 58 recede.

As soon as rollers 252 recede, belt 160 is brought down (Fig. 4) on the jacket; blade 76 advances to press the jacket seam against the belt and the belt is turned to strip the jacket from the mandrel, convey it to the place of discharge while holding the lapped parts together in cooperation with belt 175 until adhesion has been completed; the belts throw off the jackets into trough 196.

It should be understood that suction is maintained in the fork fingers from the time the fork takes a blank from the bottom of the stack and conveys it to the head 138 until the head takes up the blank; suction is maintained in duct 73 until the jacket has been applied to the mandrel and its edges lapped thereon.

Upon the parts leaving the position shown in Figs. 1, 2 and 3, cam 31, acting on lever 32, causes frame 226 to be moved on its pivot from the full line to the dotted line position of Fig. 8. In doing so gear 237 is unmeshed from gear 224, cam 238 is engaged with track 239 and the blades 236, which were previously rotated to contact roller 223, are brought to vertical position and raised alongside an arm 101 of the fork 99 into contact with the bottom blank of the stack to deposit two spaced lines of adhesive on the blank. The fingers are so positioned that the lines of adhesive will register with the spaces between the furcations of the folding plate when the blank is on the mandrel. Having raised the applicator to the blank, the cam then releases lever 32 and the spring 240, assisted by the cam, restores the lever 32 to its rest position (Fig. 16) and permits gear 237 to drop into mesh again with gear 224. Gears 224 and 202 turn constantly during the operation of the machine.

By adjusting the connection between the ear 219 and the bolt 221, the distance between rollers 202 and 223 can be varied to adjust the thickness of the film of adhesive adhering to roller 223 and hence adjust the amount which will be taken off on the ends of the applicator fingers.

From the foregoing description, taken in connection with the accompanying drawings, it is thought that the construction, operation and advantages of the invention will be clear to those skilled in the art.

While I have shown a practical and preferred embodiment of my invention I wish it understood that changes in the construction may be made without departing from the spirit of the invention within the scope of the appended claims.

I claim:

1. In a jacket forming machine wherein is provided a magazine for stacked blanks, a distant mandrel on which the jackets are formed, and means for folding the blanks about the mandrel and overlapping the sides of the blanks and causing adhesion between the overlapped parts: the improvement which comprises blank folding and seam-lapping and pressing mechanism, said mechanism including a blank lifting and primary folding head for applying a blank to the side of the mandrel opposite that where the lapping takes place and partly folding the blank about

the mandrel, and a secondary blank folding and edge lapping means comprising a blade operating against one side of the blank to carry it around the mandrel, and a roller carrying plate operating against the other side of the blank to fold it over the side engaged by the blade and press the folded parts together.

2. In a jacket forming machine: a mandrel; a reciprocating folding head; means to move said

10 head to and from said mandrel; and means cooperating with said head to pick up a blank as the head is moved toward the mandrel and apply it to and partly around the mandrel, said last named means including a mandrel-conforming groove in the head and a yieldable suction means carried by the head and projecting into the groove thereof and adapted to engage the blank on the mandrel and recede as the head folds the blank partly about the mandrel.

15 3. In a jacket forming machine: a mandrel; a reciprocating folding head; means to move said head to and from said mandrel; means cooperating with said head to pick up a blank as the head is moved toward the mandrel and apply it

20 to and partly around the mandrel, said last named means including a mandrel-conforming groove in the head and a yieldable suction means carried by the head and projecting into the groove thereof and adapted to engage the blank on the mandrel and recede as the head folds the blank partly about the mandrel; and other means operating to complete the fold and overlap the side edges of the blank on the mandrel while said head is still engaged with the mandrel.

25 4. In a jacket forming machine: a mandrel; a reciprocating folding head; means to move said head to and from said mandrel; means cooperating with said head to pick up a blank as the head is moved toward the mandrel and apply it to the mandrel and partly around the same, said last named means including a mandrel-conforming

30 groove in the head and a yieldable suction means carried by the head and projecting into the groove thereof and adapted to engage the blank on the mandrel and recede as the head folds the blank partly about the mandrel; and other means operating to complete the fold and overlap the side edges of the blank on the mandrel while said head is still engaged with the mandrel.

35 5. In a jacket forming machine: a mandrel; a reciprocating folding head; means to move said head to and from said mandrel; means cooperating with said head to pick up a blank as the head is moved toward the mandrel and apply it to the mandrel and partly around the same, said last named means including a mandrel-conforming groove in the head and a yieldable suction means carried by the head and projecting into the groove thereof and adapted to engage the blank on the mandrel and recede as the head folds the blank partly about the mandrel; and other means operating to complete the fold and overlap the side edges of the blank on the mandrel while said head is still engaged with the mandrel.

40 6. In a jacket forming machine: a mandrel; a reciprocating folding head; means to move said head to and from said mandrel; means cooperating with said head to pick up a blank as the head is moved toward the mandrel and apply it to the mandrel and partly around the same, said last named means including a mandrel-conforming groove in the head and a yieldable suction means carried by the head and projecting into the groove thereof and adapted to engage the blank on the mandrel and recede as the head folds the blank partly about the mandrel; and other means operating to complete the fold and overlap the side edges of the blank on the mandrel while said head is still engaged with the mandrel.

45 7. In a jacket forming machine: a mandrel having a shank; a support to which said shank is fastened; two opposed slides operating at the sides of the mandrel and movable laterally of the mandrel toward and from the same; a furcated blank folding blade carried by one of said slides for movement across the face of the mandrel; a roller carrying plate carried by the other of said slides and having its rollers positioned to ride over the face of the mandrel between the furcations of the blank folding blade.

50 8. In a jacket forming machine: a mandrel having a shank; a support to which said shank is fastened; two opposed slides operating at the sides of the mandrel and movable laterally of the mandrel toward and from the same; a furcated blank folding blade carried by one of said slides for movement across the face of the mandrel; a roller carrying plate carried by the other of said slides and having its rollers positioned to ride over the face of the mandrel between the furcations of the blank folding blade; and yieldable means

55 9. In a jacket forming machine: a mandrel having a shank; a support to which said shank is fastened; two opposed slides operating at the sides of the mandrel and movable laterally of the mandrel toward and from the same; a furcated blank folding blade carried by one of said slides for movement across the face of the mandrel; a roller carrying plate hinged to the other slide and having its rollers positioned to ride over the face of the mandrel between the furcations of the blank folding blade; and yieldable means

60 10. In a jacket forming machine: a mandrel having a shank; a support to which said shank is fastened; two opposed slides operating at the sides of the mandrel and movable laterally of the mandrel toward and from the same; a furcated blank folding blade carried by one of said slides for movement across the face of the mandrel; a roller carrying plate hinged to the other slide and having its rollers positioned to ride over the face of the mandrel between the furcations of the blank folding blade; and yieldable means

urging the rollers into pressure contact with the mandrel.

JACOB CUTLER.
